(22) Filed: **Jan. 31, 2014**

CLAIM

The ornamental design for electronic computer with an at least partially transparent input device, as shown and described.

DESCRIPTION

Related U.S. Application Data

(62) Division of application No. 29/423,474, filed on May 31, 2012, now Pat. No. Des. 701,501.

FIG. 1 is a top perspective view showing a design for electronic computer with an at least partially transparent input device;

(51) **LOC (10) Cl.** **14-02**

FIG. 2 is a front view thereof;

(52) **U.S. Cl.**

FIG. 3 is a back view thereof;

USPC **D14/318**

FIG. 4 is a side view thereof;

(58) **Field of Classification Search**

FIG. 5 is another side view thereof;

USPC D14/315-327; D18/1, 2, 7, 11;

FIG. 6 is a top view thereof;

235/145 A, 145 R; 341/22, 23; 345/104,

FIG. 7 is a bottom view thereof;

345/156, 168, 169, 173; 361/679.08,

FIG. 8 is a top perspective view showing a second embodiment of a design for electronic computer with an at least

361/679.09, 679.11, 679.26, 679.27

partially transparent input device;

CPC G06F 1/16; G06F 1/1616; H01R 35/02;

FIG. 9 is a front view thereof;

H03M 11/00; G09B 13/04; H03K 17/94

FIG. 10 is a back view thereof;

See application file for complete search history.

FIG. 11 is a side view thereof;

(56) **References Cited**

FIG. 12 is another side view thereof;
